FRICTION CATCH

Arthur L. Fryer, Laguna Beach, Calif.

Application January 17, 1938, Serial No. 185,395

7 Claims. (Cl. 292—76)

My invention relates to a friction catch of the type frequently designated as cupboard door catches, casement sash catches or the like. These are of the type in which a relatively light friction is overcome in closing the door or sash and a friction is developed in opening such door or sash, therefore retaining these in the closed position with sufficient security for most purposes.

Among other objections to the ordinary type of friction catches is the lack of adjustability to take up for any slackness developing in the door or sash assembly occurring from shrinkage, sagging of the hinges or the screws attaching the devices becoming slightly loose. Also in a number of types of these friction catches the resilient element which yields when the door is closed and opened does not have sufficient rigidity to prevent its being distorted after comparatively short period of usage so that it is practically useless as a catch. My invention seeks to overcome these objections by having the main or resilient friction element with sufficient rigidity so that it may yield a small amount during the closing and opening of the door or other device but may have sufficient rigidity to prevent distortion. Also in my invention an angle structure secured to the edge and face of a door has a resilient tongue-like element slit from the main body of the portion of the catch so that this tongue is sufficiently resilient to yield in closing and opening the door, yet having a sufficiently firm mounting on the door or engagement with the other portion of the angle plate or bracket to develop sufficient resistance so that the latching tongue is not permanently distorted rendering the catch inefficient.

Another object and feature of my invention is forming a friction detent which engages the tongue in such a manner that it may be adjustably mounted on the fixed cupboard wall or the frame of a window where a sash is used so that by slight adjustments a take up may be made to compensate for shrinking of the door, sagging or other disalignment which would cause the catch to be loose. In one form of my invention the adjustable detent is made in the form of a plate which by means of a screw and slot connection may be adjusted to project a desired distance into the opening in which the door or sash swings. This plate is confined in its movement by fitting in a slot-like perforation in a retaining plate secured to the edge of the door or window opening. In another form of my invention the retaining plate may have an adjustable screw of which the head of the screw operates as

the detent engaging the resilient tongue of the complementary part of the catch.

My invention is illustrated in connection with the accompanying drawing, in which:

Fig. 1 may be considered as a horizontal section taken on the line 1—1 of Fig. 2 in the direction of the arrows showing the simple form of catch in the closed position.

Fig. 2 is an elevation taken in the direction of the arrow 2 of Fig. 1.

Fig. 3 is an end view of the detent assembly taken in the direction of the arrow 3 of Fig. 1, the tongue portion of the catch being removed.

Fig. 4 is an end view of the tongue portion of the catch taken in the direction of the arrow 4 of Fig. 1 with the detent portion removed.

Fig. 5 is a section similar to Fig. 1 showing the same type of resilient tongue mounting with a modified form of detent, this using a screw type of catch.

Fig. 6 is a front elevation showing the catch used with a detent mounted on a shelf or the like.

Fig. 7 is a section on the line 1—1 of Fig. 6 in the direction of the arrows showing the detent only as mounted on a shelf.

Fig. 8 is an elevation taken in the direction of the arrow 8 of Fig. 9 of another form of the spring tongue catch assembly.

Fig. 9 is a section on the line 9—9 of Fig. 8 in the direction of the arrows.

Dealing first with the catch construction illustrated in Figs. 1 to 5 inclusive, this employs the spring tongue catch assembly 11 which is formed of an angle plate 12 having a flange 13 fitted in a recess 14 in the edge of a door or sash indicated at 15. This has right angular end pieces 16 fitting against the surface 17 of the door or sash. A tongue 18 is spaced from the flange 13 by the two parallel slits 19. These slits also continue 20 separating the ends 16 from the flat portion 20 of the tongue. The resilient portion of the tongue 21 consists of a section 22 extending outwardly from the portion 20 at an angle slightly less than a right angle. The nose portion 23 has 45 quite a pronounced slope towards the outer or tip portion 24. There is thus a slight projection 25 between the parts 22 and 23. A rear or thrust section 26 extends to the surface 17 of the door or sash and the tongue portion terminates in a 50 flattened end 27 through which a screw 28 is threaded and attaches the tongue portion to the side 17 of the door or sash. A screw 29 secures the flange portion 13 to the edge of the door or sash. These are the only two elements attach- 55

ing the resilient tongue assembly to the edge and face of the door, sash or similar construction. It is to be noted that the sash has an angular cut 38 at the junction of the recess 14 and the side 17 to allow a slight movement of the tongue section including the portion 22 and the flat portion 20 in alignment with the surface 17 of the sash or door.

10 The detent assembly 40 includes a retaining plate 41 which is shown as substantially rectangular and attached in a recess 42 in the edge of a frame member 43 of a cupboard, closet or the like. This plate has a rectangular slot 44 which is positioned slightly beyond the surface 45 of the wood member 43. An adjustable detent plate 46 is also preferably rectangular and has an elongated slot 47 through which extends an attaching screw 48. This screw holds the plate in close contact with the surface 45 of the wood member 43. The projecting tongue-like end 49 extends through the slot 44 and has a contact end 50 with slightly beveled corners 51.

15 In the operation of this catch the plate 46 is adjusted so that when the door, sash or other element approaches its closing position in relation to the wood frame member 43, a contact end 50 engages the sloping nose 23 of the resilient tongue assembly slightly outwardly from the rounder corner 25. As the door or sash is thrust to its closed position on account of the plate 46 being immoveable and held from bending by passing through the slot 44 in the plate 41, the parts 20, 22 and 23 of the tongue portion yield slightly to allow the plate 46 to ride over the corner 25 and on account of the angle of the sections 20 and 22 of the resilient tongue being slightly less than a right angle, there may be a slight clearance if desired when the door or sash is completely closed so that in opening the sash the end 50 slides over the section 22 and thus rides over the corner 25. Thus on account of the slight resiliency of this portion of the tongue it is necessary to have the cut-out corner 38 of the wood of the sash or door. In addition it will be noted that the plate 46 operates as a stop in limiting the movement of the sash or door in its closed position. Manifestly should the catch become slightly loosened due to shrinkage of the wood construction, the plate 46 may be adjusted by slightly loosening the screw 48, moving this plate in a desired position and again tightening the screw. It is not necessary to make any changes in the position of the screw 28. This end the screw 29 are left permanently in position, thus holding the resilient tongue assembly of the catch attached in a non-adjustable manner to the door or sash. There is sufficient stiffness developed by the connection of the front portion of the tongue through the rear placing portion 26 to the flat portion 27 so that the tongue after prolonged use does not become distorted out of shape.

20 In Fig. 5 I show the same type of spring tongue assembly designated by the numeral 11 shown in connection with Figs. 1, 2 and 4. In this case, presuming that the tongue part of the catch is mounted on a door or sash, the detent assembly 50 is illustrated as mounted on an end wall 51 or else this may be considered as a shelf. In this construction a flat plate 52 is attached to the wood construction 51 by a screw 53. An additional screw catch 54 is threaded through an opening 55 in the plate and this has a projecting head 56 with the usual screw driver kerf. The head of the screw 54 projects, that is, the screw 75 is not threaded tight against the plate and in

fact, it is preferable to use a rounded head screw so that the screw engages with the spring catch reacting against the portions 22 and 23 and the slight projection 25. Such an arrangement therefore forms a simple connection for engaging the spring tongue catch and on account of the screw being readily adjustable, the pressure against the catch may be readily varied. This in effect gives a somewhat similar adjustment to that shown in connection with Figs. 1 and 2.

10 In Figs. 6 and 7 I show a modification of the assembly suitable for the catch operating in conjunction with a detent assembly mounted on a shelf. In this instance a shelf board is designated as 60. On this is mounted a detent assembly 61 which consists of a strap 62 pivoted by a screw 63, the strap having an upturned detent end 64. The strap has an arcuate slot 65 concentric with the pivot 63 and the detent may thus be clamped in adjusted position by a clamping screw 66. One edge of the detent end 64 engages the tongue of the catch which may be similar to that of Fig. 1 or 8 and 9.

25 In Figs. 8 and 9 I illustrate a modified construction of the spring tongue assembly which may be used with any of the above types of detent construction or other detent-like devices. This employs an angle plate 70 having a flange 71 secured by a screw 72 to the edge of a sash or door indicated at 73. This plate has a right angular bent section 74 fitting against the face 75 of the door or sash. A rigid projecting nub 76 which includes the side arms 77 and the back or thrust section 78, the flattened end 79, contacts the surface 75 and is secured by a screw 80. There are a pair of slits 81 which have end portions 82 in the flange 71. These extend to slits 83 in the angle section 74 and slits 84 in the front portion of the projecting nub 76. This construction thus develops a free tongue 85. This tongue has a base portion 86 slightly depressed from the section 74 of the main portion of the plate. The outwardly extending face 87 is at slightly less than a right angle to the base 86. There is a slight projection 88 and the curved portion 89. These parts or surfaces pressed by 71, 78 and 89 are shaped to correspond substantially to the portions 22, 25 and 23 respectively of the catch construction of Figs. 1 and 4. In this case however there is a cross slit 90 which separates the tip end 91 of the tongue from the main portion of the plate. Therefore this tongue may be pressed backwardly until it contacts the edge 92 at this slit 90. This therefore gives a rigid backing and support for the resilient tongue. It permits the tongue to have a somewhat free motion due to its resiliency when engaged by any of the detents above described or those of a similar type, yet when the end 91 contacts the edge 92 the tongue has a substantially rigid support and the resiliency results from a slight bending at the angle projection 88. With this construction should the tongue become pressed back too far so that the end 91 always contacts with the edge 92 or is too close to this edge, it may be sprung by using a screw driver or similar tool outwardly so as to normally leave a space between the end 91 and the edge 92. It will thus be seen that the construction of Figs. 8 and 9 is in its principle of operation substantially the same as the spring tongue construction illustrated in detail in Figs. 1, 2, 4 and 5.

30 In Fig. 6 I show a modification of the catch which may be applied either to that of Fig. 9 or the type of Fig. 1. The illustration however showing this element as a modification of the catch 75

of Figs. 8 and 9 in which a flat plate member 95 forms the equivalent of the flange 71 only straightened out to align with the rear flattened end 79. This allows the catch to be applied to a flat surface as it is not necessary that it be made angular to attach to an edge and a face of a door or sash member. The other features having to do with the nub construction with the resilient tongue are illustrated the same as in Figs. 8 and 9 but manifestly could be made the same as shown in Figs. 1, 2 and 4.

Various changes may be made in the details of the construction without departing from the spirit or scope of the invention as defined by the appended claims.

I claim:

1. A catch defined by a plate having an unslit portion with means for attachment to a door, there being a pair of parallel slits extending in a direction away from the attachment means and defining a tongue between the slits, the tongue having a flat portion to be substantially in alignment with one surface of the door, a face portion of the tongue extending outwardly from the flat portion at an angle slightly less than a right angle, a nose refining an obtuse angle from the face and receding from the flat portion of the tongue, there being a projection between the face portion and the nose and a rigid structure reacting against the nose and the projecting portion of the tongue and resisting deformation of the face and the nose portion when the tongue of the catch passes over a keeper attached to a fixed structure.

2. A catch having a plate with a flange with means for attachment to the edge of the door, the plate having a pair of parallel slits extending from the attachment means and provided with end pieces at right angles to the flange to engage the face of a door, the flange being attachable to a door, there being a tongue with parallel sides between the said slits, said tongue having a flat portion substantially in the plane of the face of the door between the end pieces, a face portion of the tongue extending outwardly from the flat portion at an angle slightly less than a right angle, a receding nose forming an obtuse angle with the face and defining a projection between the face and the nose portion and a fixed structure reacting against the distorting movement of the nose, the projection and the face when these pass over a contact end of the keeper in opening and closing a door.

3. A catch defined by a single integral plate having a flat portion with means for attachment to a flat surface, there being a pair of parallel slits extending from the portion of the plate having the attachment means and defining a tongue with parallel sides between the slits, the slits having end pieces extending along the side of the tongue, the tongue having a flat portion substantially in alignment with a surface of the door and having a face extending outwardly from such surface at an angle less than a right angle, a receding nose at the outer end of the tongue forming an obtuse angle with the said

face and defining a projection between the face and the nose and means to restrict the displacing movement of the face, projection and nose portion by a keeper riding over such portions in opening or closing a door.

4. A catch including a plate with means to attach an end portion to a door, the plate having a pair of parallel slits and a tongue between the slits, the tongue having a flat portion substantially aligned with the flat surface of a door 10 and having an outwardly extending face at an angle slightly less than the right angle with the face, a receding nose at an obtuse angle with the face and defining a projection between the face and the nose, the tongue having a reverse 15 bend with a thrust section extending towards the flat surface of a door and an anchoring means securing the thrust portion to such surface whereby the thrust portion of the tongue and the anchoring means resists the distortion of the nose, 20 the projection and the face when riding over a contact edge of a keeper in opening and closing the door.

5. A catch formed of a plate having a flat end portion with means for attaching to a door, there 25 being a pair of parallel slits extending from the said end portion and having end pieces, a tongue attached to said end portions only between the slits and the end pieces, the said tongue having a flat section and a face extending outwardly at 30 slightly less than a right angle and a receding nose at an obtuse angle from the face defining a projection between the face and the nose, a reverse bend at the outer end of the nose, a thrust section extending from the reverse bend, a flattened end forming an extension of the thrust section and means for attaching the said flattened end to a door or the like whereby the thrust section resists the distortion of the nose, the projection and the face by a keeper riding over such 40 nose, projection and face in opening or closing a door.

6. A catch having a plate with means for attachment to a door, a resilient tongue integral with the plate and having a reverse bend, there 45 being a nose portion adjacent the reverse bend and a projection on one face of the tongue, the tongue having an extension portion to engage a surface of the door and means to anchor such extension to the surface of the door whereby the 50 distortion of the tongue by a keeper riding over the nose and the projection in opening and closing of the door is resisted by the said anchor.

7. A catch having a plate with means for attachment of one end to a door, a resilient tongue 55 having a flat surface to align with the flat surface of a door and having a face extending outwardly at a slightly less than a right angle, the tongue having a reverse bend and a thrust section with means to anchor the thrust section to a door, there being a slight projection between the face and the reverse bend, the thrust section and anchor resisting the distortion of the tongue by a keeper riding over the said projection in 60 opening or closing a door.

ARTHUR L. FRYER.
